UNITED STATES PATENT OFFICE.

RUDOLF LOEB, OF JENKINTOWN, PENNSYLVANIA.

SEWING-MACHINE.

1,238,033.

Specification of Letters Patent. Patented Aug. 21, 1917.

Application filed December 31, 1913. Serial No. 809,798.

To all whom it may concern:

Be it known that I, RUDOLF LOEB, a citizen of the United States, and a resident of Jenkintown, Montgomery county, Pennsylvania, have invented certain Improvements 5 in Sewing-Machines, of which the following is a specification.

The object of my invention is to provide a sewing machine of the embroidery type, 10 more particularly adapted for the formation of eyelets or eyelet embroidery, which eyelets may be circular, or may have a substantially oval contour, or be pointed at one end and join a semi-circular portion at the opposite end.

The machine which I employ for applying 15 stitches to the edges of the preformed apertures is substantially like that disclosed in my pending application filed January 14, 20 1913, Serial No. 741,948, and the means whereby I am enabled to stitch the edges of the preformed apertures to effect the eyelet embroidery is in the nature of an attachment to said machine. It will be understood, however, that such attachment 25 may, with slight modifications, be applied to other sewing machines of a type substantially like the one illustrated in the accompanying drawings.

30 The mechanism for effecting the desired result and forming the subject of my invention is more fully described hereinafter, reference being had to the accompanying drawings, in which:

35 Figure 1, is a side elevation of a sewing machine having and containing the improvements forming the subject of my present invention;

Fig. 2, is a plan view of the same;

40 Fig. 3, is a side elevation, partly in section, of the eyelet forming mechanism;

Fig. 4, is a plan view of the eyelet forming mechanism; the bed of the machine being broken away to more clearly illustrate 45 the same;

Fig. 5, is an end elevation of the front of the machine;

Fig. 6, is a detached view of certain parts of the mechanism, omitting the head and 50 frame;

Fig. 7, is a detached perspective view of the fabric-holding means;

Fig. 8, is a perspective view of a portion 55 of the sliding bed-plate showing co-operative means for use with said fabric-holding means;

Fig. 9, is a sectional view of the fabric-holding means;

Figs. 10 and 11, are views illustrating 60 details of my invention, and

Figs. 12, 13 and 14, are views illustrating successive stages in the formation of one form of the eyelets.

As before noted, the machine for effecting 65 the formation of the stitches is of a character substantially similar to that illustrated in my pending application, and the needle operating mechanism is controlled by a series of cams and adjusting elements as disclosed therein; all of which is substantially as follows:

In the drawings, 1 represents the frame 70 of the machine; 2 the head, in which are contained the means for effecting vertical reciprocation of the needle-bar 3 which, in this type of machine is pivotally mounted 75 so as to be capable of vibrating under the action of suitable mechanism. In this connection, it may be noted that the mechanism for imparting vertical reciprocation to the 80 needle-bar is old and well known in the art, and no extended reference thereto will be made herein. The needle-bar carries a needle of any ordinary or usual type, indicated at 5, which may be secured to said bar by a 85 set screw 6.

In the lower part of the head of the machine I provide an arm 15, pivoted at 16 and having a sleeve 17 pivoted thereto at 18; said sleeve encircling the said needle-bar 90 and through which said needle-bar may slide during its vertical reciprocation. Movement imparted to the arm 15 effects vibration of the needle-bar, and for this purpose the following mechanism may be employed, which mechanism includes means for adjusting or regulating the extent of 95 such movement.

Suitably carried by the frame of the machine is a countershaft 20, having a gear 100 wheel 21 which receives motion from a gear wheel 22 on a main driving shaft 23. The opposite end of said countershaft carries a cam 24, with which engages a roller 25 carried by an arm 26 connected to a rock shaft 105 27 suitably journaled in or on the frame of the machine, and having at one end a substantially yoke-shaped lever 28, one end of which engages with a pin 29 adapted to slide in the head of the machine and impinge 110 upon the arm 15. The yoke-shaped lever is provided with adjustable screws 31 and

32 forming contact points; said screws having lock nuts 33 whereby they may be retained in any predetermined position of adjustment.

5 Return movement of the arm 15, when the roller-carrying arm 26 is released from the action of the high side of the cam, is imparted by means of a flat spring 35, suitably connected to the head of the machine 10 and having an end 36 bearing against said arm 15. Upon rotation of the countershaft 20, movement is imparted to the cam 24 and transmitted to the arm 15 for the purpose of vibrating the needle-bar and its attached 15 parts by the means just described; reverse movement of said needle-bar being accomplished by the spring referred to.

The extent of movement of the bar by the cam 24 and roller arm 26 is determined by 20 the size of said cam, while the position of the needle-bar, needle and presser foot with respect to the slot in the stitch plate is determined by the adjusting screws 31 and 32; one being set in and the other out, as the case 25 may be, and the upper one, indicated at 31, for instance, bearing upon the frame of the machine.

The arm or lever 26 is in two parts, hingedly connected together by a pin 26^a and 30 held in operative condition by a pin 40^a slidably mounted in said arm or lever, which pin 40^a is in operative engagement with the end 40^b of a bell crank lever 40 which is pivoted to said arm or lever 26 at 41. When 35 this pin 40^a is withdrawn, in the manner hereinafter described, the cam 24 may move the end of the lever 26 on the pivot pin 26^a without affecting the rock shaft 27.

In addition, however, I have provided 40 means in the shape of a bell-crank lever 40 pivoted at 41 to a projection carried by the lever or arm 26, which bell-crank lever is operatively connected to a rod, in a manner hereinafter described, under the control of a 45 knee-lift (not shown) employed with this type of machine, under control of the operator. Operation of said knee-lift to the full extent in a manner common to machines of this type stops the vibration of the needle; permitting it to reciprocate vertically and 50 form tacking stitches in order to stop off the thread employed in the binding or edging of the apertures of the fabric. These apertures are preferably preformed.

55 The means for holding and effecting stitching or edging of these apertures in the fabric may be described as follows:

The bed-plate 55 of the machine is recessed or apertured at 56, and adapted to 60 said recess or aperture is a plate 57; in the present instance arranged to slide upon ways 58 formed in the sides of the recess or aperture of said bed-plate, and this plate carries means for holding the fabric; such means 65 permitting complete or partial rotation of

the fabric from a single axis in the plane of the vibrations of the needle. Mounted on this plate 57 is a bracket 60 to which a lever 61 is pivoted at 62; one end of said lever being connected to a post 63 carrying the 70 fabric-holding mechanism, generally indicated at 64; said post having a lug 65 adapted to a slot 66 in the end of said bracket whereby movement imparted thereto will be effected in a vertical direction, and a spring-pressed plunger 67 mounted in a casing 68 is employed to hold the rear end of said lever up so that the fabric-holding element may be maintained in the lower position for 75 operative engagement with the fabric. 80

Pivoted at 69 on the under side of the machine is a lever 70, which is connected by means of a link 71 with the lever 61 pivoted to the bracket. This lever 70 carries a lug 72 which may be provided with 85 a roller 73, for a purpose to be described.

Suitably connected to a rock shaft 75, which may be journaled in bearings beneath the bed-plate of the machine is a block 76 having an arm 77 bearing upon the roller 73, 90 and an arm 78 to which a spring 79 is attached; the opposite end of said spring being anchored at 80 to the frame or bed-plate whereby the normal position of said block 76 will maintain the arm 78 of the same out 95 of operative engagement with the roller 73.

Depending from the shaft 75 is an arm or rod 82 to which a knee lever under the control of the operator may be attached, (not shown) and when said knee lever is moved 100 to the right, the lever 70 is depressed and the fabric-holding means raised for the positioning of the fabric beneath the same.

Operatively connected with the stitch controlling mechanism is a rod 85 which is 105 maintained in its upper position by means of a spring 86; such rod extending through the bed-plate 55 and having at its lower end a collar 87 which may be secured by a set screw 88; which collar lies in the path of a 110 projection 70^a on the end of the lever 70 so that when the knee lever is operated to raise the fabric-holding means, said rod 85 will be lowered against the tension of the supporting spring. 115

This action effects movement of the bell-crank lever 40 and causes it to withdraw the pin 40^a and render inactive the arm or lever 26 operated by the cam 24, thereby stopping movement of the rock shaft 27 and its lever 120 28 controlling the length of the stitches. For this purpose the rod 85 is provided with a projection 85^a which engages one end of said bell-crank lever 40 when said rod is lowered.

The fabric-holding means 64 is more clearly described in Figs. 7, 8 and 9, wherein it is seen to consist of a circular element 90, which receives a series of rings 91, 92 and 93, properly secured together by clips 94 130

carried by one of said rings; the ring 93 being channeled at 95 on its under side for the reception of a ring of rubber or similar material, indicated at 96, and being grooved 5 on its upper side at 97 for the reception of balls 98 interposed between the same and a similarly formed groove in the ring 92, thereby forming a ball-bearing and permitting ready rotary movement of the rubber-shod lower ring with respect to the rest of the structure.

The sliding plate 57 is provided with a circular plate 99 disposed concentrically with respect to the rubber-shod foot plate or ring 15 93 of the fabric holding means and being grooved for the reception of balls 100 whereby an anti-friction bearing between the same and the recess 101 in the sliding plate 57 receiving the same is provided; said circular 20 plate 99 being roughened on its upper surface and held in place by a central clamping plate 102, which may be secured by screws 103. This clamping plate and the sliding plate 57 are notched or recessed at 104 for 25 movement with respect to a fixed needle guide 105 projecting through the same and coöperating with the needle.

The bracket 60 carrying the fabric-holding means is longitudinally movable with 30 respect to the bed-plate of the machine, and is provided with a locking pin 106 controlled by a spring 107 to maintain the fabric-holding means with its axis coincident with the plane of vibration of the needle; such pin being arranged to enter an 35 aperture 108 in said sliding plate.

Pivotedly mounted beneath the bed-plate is a two-armed lever 110; one arm being under the control of a spring 111, while the 40 opposite arm is in engagement with the pin 106, being secured thereto by nuts 112. This arm (110^a) of the lever carries on its under side a hook 115, to which a chain 116 is attached; the lower end of the same being 45 connected to an ordinary foot treadle (not shown). By pressing this treadle, the pin will be removed from the sliding plate carrying the fabric-holding means 64, and the operator may move such plate, for a purpose 50 to be described.

As may be readily seen upon reference to Fig. 3, the sliding plate 57 is mounted so as to have slight longitudinal movement with respect to the bed-plate of the machine, 55 which movement is under control of the operator.

The member 91 of the fabric-holding means in the form of an annular ring is of a peculiar shape; being substantially undulatory, as indicated in Fig. 9, so that springs 60 91^a may be interposed between it and the element 90 to insure pressure upon the rubber ring or foot 96 for holding the fabric against the rotatable plate 99. Two or more 65 springs may be employed, as may be desired,

to insure proper tension upon the material being embroidered.

Upon examining Figs. 12, 13 and 14, it will be noted that the fabric as prepared for embroidery has a number of preformed apertures 120 therein, some of which are pointed at one end and join semi-circular portions at the opposite end, which apertures are to have their edges stitched or seamed. The fabric is held stretched in an ordinary 75 tambour frame (not shown) commonly employed in embroidering machines, and this tambour frame is laid over the bed-plate of the machine; the fabric-holding means being raised to permit the proper positioning 80 of the fabric beneath the same, and the operator then manipulates said tambour frame so as to bring the point *a* of the fabric, (see Fig. 12) directly opposite the plane of vibration of the needle; the sliding plate 57 carrying the bracket which supports the foot being held by the pin 106. As soon as this position is determined, the pin is released, (in the manner described), and the operator grasping the bracket 60 by hand moves the 85 same to the right, away from and out of control of said pin 106. The stitch operating mechanism of the machine is then set in motion; the preliminary short stitches indicated at *a* being first placed, and then while the said needle is vibrating to and from the operator, the bracket is slowly moved to the left, effecting the formation of the substantially paralleling stitches on the upper edge of the aperture, as indicated in 90 Fig. 12. As soon as the point *a* is reached, the pin 106 automatically enters the aperture or recess 108 in the sliding plate, preventing further movement to the left of said plate and indicating that the stitching to 105 that extent at least has ceased. The operator then rotatively turns the fabric; a movement of which may readily be effected by reason of the holding means above described; the rubber pad on the under side 110 thereof holding the fabric against the turn-table plate, and the two being movable with a minimum of friction owing to the ball bearings employed, which has the effect of stitching the semi-circular end, in the manner 115 indicated in Fig. 13, which brings the stitched portion to the condition and position shown in Fig. 14, and then by releasing the pin 106 and effecting further movement of the bracket to the left, the completion of 120 the stitching around the eyelet may be effected. The other apertures are stitched in a similar manner.

I claim:

1. In an eyelet forming machine, the combination of stitch forming means, a horizontally disposed manually operable slidable plate, means for limiting the movement of said plate in both directions while making an eyelet, and rotatable fabric-holding 125 130

- 4 means manually operable carried by said plate; said rotatable fabric-holding means being operable when the plate reaches the limit of movement in one direction and said movement limiting means serving as a lock for holding the plate in position to permit operation of said rotatable fabric-holding means.
5. In an eyelet forming machine, the combination of stitch forming means, a manually operable slidable supporting member, rotatable and vertically movable fabric-holding means carried by said slidable supporting member, locking means for said supporting member, and means for lifting the fabric-holding means, said fabric-holding means being manually rotatable at the end of the movement of said supporting member.
6. In an eyelet forming machine, the combination of stitch forming means, a manually operable sliding plate, means for locking said plate, means for releasing the same, fabric-holding means carried by said plate, said fabric-holding means being rotatable, and means for laterally vibrating said stitch forming means during the sliding movement of said plate and the rotary movement of said fabric-holding means.
7. In an eyelet forming machine, the combination of stitch forming means, a manually operable sliding plate, means for locking said plate, means for releasing the same, fabric-holding means carried by said plate, said fabric-holding means being slidable with the plate and rotatable with respect thereto, and means for laterally vibrating said stitch forming means during the sliding movement of said plate and the rotary movement of said fabric-holding means.
8. The combination, in a machine for forming eyelets, of a manually operable sliding plate, fabric-holding means carried thereby, locking means for said plate, a lever mounted on said plate in engagement with the fabric-holding means, means tending to hold said fabric-holding means in the lowered position, and knee-controlled means for operating said lever to elevate said fabric-holding means.
9. In an eyelet machine, the combination of a slidable plate having a rotary turntable, ball bearings therefor, a fabric-holding member cooperating with said turntable, ball bearings for said fabric-holding member, the latter being rotatable with respect to said slidable plate, and vibrating stitch forming mechanism combined therewith, said fabric-holding member being adapted to rotate during the operation of the stitch forming mechanism to lay radial stitches.
10. In an eyelet machine, the combination of a frame, a slidable member carried thereby, a bracket supported by said slidable
- member, fabric-holding means vertically movable in said bracket, means for elevating the fabric-holding means, said fabric-holding means comprising a plurality of circular plates, a holder therefor, and springs interposed between the holder and rings whereby the holder may properly engage the goods.
11. In an eyelet forming machine, the combination of laterally vibrating stitch forming means, a manually operable sliding member having a rotary turntable, rotatable fabric-holding means cooperating with said turntable, and friction producing means for said fabric-holding means rotatable therewith.
12. In an eyelet forming machine, the combination of laterally vibrating stitch forming means, a manually operable sliding plate, rotatable fabric-holding means carried by said plate, and a friction producing device for said fabric-holding means rotatable therewith, and means for arresting the lateral vibrations of said stitch forming means.
13. In an eyelet forming machine, the combination of laterally vibrating stitch forming means, a manually operable sliding plate, rotatable fabric-holding means carried by said plate, and a friction producing device for said fabric-holding means rotatable therewith, and means for arresting the lateral vibrations of said stitch forming means.
14. In an eyelet forming machine, the combination of laterally vibrating stitch forming means, a manually operable sliding supporting member, fabric-holding means carried by said supporting member, means for raising said fabric-holding means and arresting the lateral vibrations of said stitch forming means, and a rotatable friction producing device for said fabric-holding means.
15. In an eyelet forming machine, the combination of laterally vibrating stitch forming means, a manually operable sliding plate having a turntable, fabric-holding means carried by said plate, means for locking said plate with the axis of the fabric-holding means in the plane of vibration of the stitch forming means, and a friction producing device for said fabric-holding means rotatable with said turntable when the sliding plate is in the locked position.
16. In an eyelet forming machine, the combination of laterally vibrating stitch forming means, a manually operable sliding plate having a turntable, fabric-holding means carried by said plate, means for locking said plate with the axis of the fabric-holding means in the plane of vibration of the stitch forming means, and a friction producing device for said fabric-holding means rotatable with said turntable when the sliding plate is in the locked position.
17. In mechanism for forming eyelet embroidery, the combination of laterally vibrating stitch forming means, a manually operable sliding plate having a turntable, fabric-holding means carried by said plate, means for locking said plate, means for releasing the same, fabric-holding means carried by said plate, said fabric-holding means being vibrated during the sliding movement of said plate and the rotary movement of said fabric-holding means, a friction producing device for said fabric-holding means rotatable with said turntable, and a ball bearing for said friction producing device.
18. In mechanism for forming eyelet embroidery, the combination of stitch forming means, a manually operable sliding plate, means for locking said plate, means for releasing the same, fabric-holding means carried by said plate, said fabric-holding means

being slidable with the plate and having a portion rotatable with respect thereto, means for laterally vibrating said stitch-forming means during the sliding movement of said plate and the rotary movement of said fabric-holding means, and a friction producing device for the rotatable portion of said fabric-holding means.

14. In an eyelet machine, the combination of a horizontally slidable plate manually operable and having a rotary turntable, a fabric-holding member coöperating with said turntable and rotatable with respect to said sliding plate, and laterally vibrating stitch forming mechanism combined therewith, said fabric-holding member being manually rotatable during the operation of the stitch forming mechanism whereby radial stitches may be laid on the fabric.

20 15. The combination, in a machine for forming eyelets, of a manually operable sliding plate having a turntable, rotatable fabric-holding means carried by said plate and coöperating with said turntable, a lever 25 mounted on said plate in engagement with the fabric-holding means, a rod connected to said lever, a spring for holding said fabric-holding means in the lowered position, and knee controlled means operatively 30 connected to said rod for elevating said fabric-holding means.

16. The combination, in a machine for forming eyelets, of a manually operable sliding supporting member having a turntable, 35 fabric-holding means carried by said supporting member and rotatable with said turntable, a lever mounted on said supporting member in engagement with the fabric-holding means, a rod connected to said lever, 40 a spring for holding said fabric-holding means in the lowered position, knee-controlled means, for elevating said fabric-holding means, and an independent friction producing device for the fabric-holding means.

45 17. In an eyelet forming machine, the combination of a slidable supporting member having a rotary turntable, a fabric-holding member coöperating with said turntable, said fabric-holding member being rotatable 50 with respect thereto, laterally vibrating stitch-forming mechanism combined therewith, said sliding member being manually

operated and said fabric-holding member being manually rotated during the operation of the stitch forming mechanism to lay 55 radial stitches, and a friction producing device for said fabric-holding means rotatable therewith.

18. In an eyelet machine, the combination of a frame, a movable supporting member 60 carried thereby, a bracket carried by said supporting member, fabric-holding means vertically movable in said bracket, said fabric-holding means comprising a plurality of rotatable rings, a holder therefor and flat 65 tension springs interposed between the holder and one of said rings whereby the holder may properly engage the goods, and means for lifting said fabric-holding means from engagement with the goods.

70 19. In an eyelet machine, the combination of a slidable plate having a rotary turntable, ball bearings therefor, a fabric-holding member coöperating with said turntable, ball bearings for said fabric-holding member, 75 slidable means carrying said fabric-holding member, the latter being rotatable with respect to said slidable means, vibrating stitch-forming mechanism combined therewith, said fabric-holding member being 80 rotated during the operation of the stitch forming mechanism to lay radial stitches, and friction producing means for said fabric-holding means.

20. In an eyelet machine, the combination of a frame, a slidable plate carried thereby, a bracket supported by said slid- 85 able plate, fabric-holding means vertically movable in said bracket, said fabric-holding means comprising a plurality of rotatable 90 rings, a holder therefor and flat tension springs interposed between the holder and one of said rings whereby the holder may properly engage the goods, ball bearings for said rings, and means for lifting said 95 fabric-holding means from engagement with the goods.

In testimony whereof, I have signed my name to this specification in the presence of two subscribing witnesses.

RUDOLF LOEB.
